CIGARETTE STUB PULLING AND
EXTINGUISHING DEVICE

James Asa Ausbrooks, Florence, Ala.

Application November 3, 1933, Serial No. 696,593

8 Claims. (Cl. 131—51)

My invention relates to improvements in devices for pulling cigarette stubs from holders, and for extinguishing them, and it consists in the combinations, arrangements and constructions herein described and claimed.

An object of my invention is to provide a device which is adapted to be used primarily in connection with an ash tray and which has a means for positively pulling a short cigarette stub from a holder, thereby obviating the necessity of using the fingers.

A further object is to provide an extinguishing means so disposed in relation to the stub pulling device that when the stub is pulled it will be immediately extinguished.

A further object is to provide a device of the type described which is readily removed from its base, such as an ash tray, so as to permit the latter to be emptied and which may be instantly replaced and will be held rigidly in position.

A further object is to provide a cigarette stub pulling means with a receptacle for water normally disposed underneath the stub pulling device and being held rigidly in position, but which can be readily removed for emptying the water or changing it.

Other objects and advantages will appear in the following specification and the novel features of the invention will be particularly pointed out in the appended claims.

My invention is illustrated in the accompanying drawing forming part of this application, in which;

Figure 1 is a perspective view showing one embodiment of my invention.

Figure 2 is a central vertical cross section.

Figure 3 is a horizontal section along the line 3—3 of Fig. 2, and,

Figure 4 is a perspective view of a detachable water receptacle.

In carrying out my invention I make use of a base portion which in the present instance is shown as an ash tray. This has the usual bottom 5, and sides 6, with rests 7 for cigars or cigarettes.

Extending centrally of the bottom or base portion 5 is a post 8 preferably made of a solid piece of metal and soldered, welded or otherwise secured to the base 5. A sleeve 9 shaped to conform to the contour of the post 8, which in the present instance is rectangular in cross section, fits over the post in sliding or telescopic relation. Secured to the sleeve 9 is a holder 10 for matches. On the opposite side of the sleeve is a loop 11 arranged to receive a tongue 12 of a receptacle 13 for hold-

ing the receptacle in position. The latter, as will be observed, may rest on the bottom 5.

At the upper end of the sleeve 9 is pivotally mounted a blade 14 having a tooth 15 extending therefrom. This blade is so constructed that when it is turned upwardly, as shown in full lines in Figs. 1 and 2, it will engage a portion 9a of the sleeve, which acts as a stop member for preventing further rotation. The blade 14 as will be observed, is pivoted at 16 and may swing downwardly into the dotted line position, as shown in Fig. 2.

From the foregoing description of the various parts of the device the operation thereof may be readily understood. In the use of cigarette holders, the smoker will often let the cigarette burn down to a point where there is very little left of the stub. In extracting the stub he is liable to burn his fingers or to crumple the burning tobacco which may drop on his clothing. With the present invention all that is necessary is to raise the blade 14 from its dotted line to its full line position, and then engage the stub with the tooth 15 and the stub will be pulled from the holder. This may be done by bringing the stub against the tooth and then pulling outwardly or by thrusting the cigarette directly against the point of the blade, whereupon the tooth will engage the stub and pull it from the holder. The receptacle 13 being located immediately beneath the plate will receive the stub which falls from the holder and the water placed in the receptacle 15 will extinguish the stub, thereby preventing any danger of fire and obviating the odor of the burning stub.

The stub puller, as stated, is used ordinarily in connection with an ash tray as shown, and in order to prevent the snagging of clothing or the tooth 15, as for instance where one reaches over to deposit ashes in the tray, the blade may be swung down into the dotted line position as shown in Fig. 2. It will be observed that the tooth 15 when in this position, is protected on one side by the sleeve 9 and on the outer side by the back of the blade itself, thus preventing the snagging of the clothing and of the fingers. The blade 14 is preferably held frictionally, like a knife blade, and may be swung to operative position, as well as the blade of a jack knife. It may be necessary at times to empty the ash tray where there is no necessity to empty the water receptacle. In such instance the sleeve is grasped and pulled upwardly off from the post 8, the ash tray can be emptied, and the sleeve replaced. At other times it may be necessary to empty and

refill the water receptacle when there are no ashes to dispose of in the tray itself. In this instance the water receptacle is lifted until the tongue 12 disengages the loop 11 when the contents of the receptacle 13 may be dumped and fresh water put into the receptacle, and it may then be replaced, ready to receive lighted stubs drawn by the tooth 15 for extinguishing them.

I claim:

- 10 1. The combination of a base having an upright, a toothed member secured to said upright, a receptacle disposed underneath said toothed member for receiving an article falling from said toothed member.
- 15 2. The combination with a base, an upright carried thereby, a toothed member projecting from said upright, a receptacle disposed beneath said toothed member to receive a burning article falling therefrom, and means within the receptacle to extinguish the fire.
- 20 3. The combination with a base, of an upright secured thereto, a toothed member projecting from said upright and adapted to engage a cigarette stub in a holder and drag the stub from the holder when the holder is being pulled away from the stub and a receptacle disposed beneath the toothed member for receiving the stub after its extraction from the holder.
- 25 4. The combination with a base, of an upright secured thereto, a toothed member projecting from said upright and adapted to engage a cigarette stub in a holder and drag the stub from the holder when the holder is being pulled away from the stub, a receptacle disposed beneath the toothed member for receiving the stub after its extraction from the holder, and means within the receptacle for extinguishing fire in the stub.

5. The combination with a base, of an upright secured thereto, a toothed member projecting from said upright and adapted to engage a cigarette stub in a holder and drag the stub from the holder when the holder is being pulled away from the stub, a receptacle disposed beneath the toothed member for receiving the stub after its extraction from the holder, and a fire extinguishing liquid in said receptacle.

80 6. The combination with a base portion having an upstanding post, a telescopic sleeve carried by the post, a pivoted blade carried by the sleeve and having a tooth, a removable receptacle disposed beneath the toothed blade and having a fire extinguishing liquid therein.

85 7. A cigarette stub pulling device comprising a base portion, an upright post carried thereby, a telescopic sleeve arranged to slide on said post, a blade pivotally secured to said sleeve and provided with a tooth, said blade having a stop member arranged to engage the sleeve to limit the pivotal movement in one direction, said blade being movable to direct the point of the tooth toward the post for protection from the tooth, and a receptacle disposed underneath the toothed blade for receiving burnt stubs pulled from holders by the tooth, and containing a fire extinguishing liquid.

90 100 8. The combination of an ash tray, a central support carried thereby, a telescopic sleeve arranged to slide on said support, a toothed blade secured to the sleeve, a fire extinguishing receptacle secured to the sleeve underneath said toothed blade on one side of said sleeve, and a match receptacle secured to said sleeve on the other side.
